UNITED STATES PATENT OFFICE.

CLAUS LEVINSEN, OF BROOKLYN, NEW YORK.

PRESSURE CHECK-VALVE.

1,296,411.

Specification of Letters Patent.

Patented Mar. 4, 1919.

Application filed March 21, 1917. Serial No. 156,324.

To all whom it may concern:

Be it known that I, CLAUS LEVINSEN, a citizen of the Danish Monarchy, and resident of Brooklyn, in the county of Kings 5 and State of New York, have invented certain new and useful Improvements in Pressure Check-Valves, of which the following is a specification.

The object of my invention is to provide 10 an improved check valve especially adapted for use in marine steam power plants in order to improve the operation thereof with respect to safety, efficiency and automatic action. Another object of my invention is 15 to provide a check valve especially adapted for use in combination with the steam regulating valves described in my pending applications numbered serially 131,852 and 141,439 respectively. Another object of my 20 invention is to provide a check valve adapted to be operated against a substantially constant pressure and containing certain novel features of construction and adjustability. Still another object of my invention 25 is to provide a special air valve for use in connection with my improved check valve. Accordingly my invention comprises the combinations of parts and elements herein-after set forth including a pressure check 30 valve and an air valve constructed and operated in accordance with my invention, reference being had to the accompanying drawing in which—

Figure 1 is a diagrammatic illustration of 35 a marine steam power plant including my pressure check valve and air valve;

Fig. 2 is a vertical sectional view on line 2—2 of Fig. 1 of the steam regulating valve with which the said valves are operated;

Fig. 3 is a vertical sectional view on line 3—3 of Fig. 4 of the pressure check valve;

Fig. 4 is a side view of the said valve;

Fig. 5 is a plan view thereof with parts broken away; and

Fig. 6 is a sectional view of the air valve.

Referring to Fig. 1, the numeral 1 designates a marine steam engine connected in the usual manner to its condenser 2. 3 is the steam supply pipe. 4 and 5 indicate some of the auxiliary power units required for the operation of a vessel. Thus 4 may represent the generator unit for electric power and 5 may be the refrigerating machine. There are other auxiliary power units required, but I have shown two only

as being sufficient for the purpose of understanding my present invention. The number of auxiliary units, their arrangement and location are immaterial so far as this invention is concerned. The auxiliary 60 units are supplied with steam from the boiler (not shown) through the steam pipes 6 controlled at each unit by the usual valves 7, 7. The exhausts of the auxiliary units are connected by pipes 9, 9 to the steam 65 regulating valve 10 which is connected at 11 to the condenser and at 12 to the atmosphere by way of the common exhaust 13. As described in the applications aforesaid, the object of the steam regulating valve 10 is to 70 connect automatically the exhausts of the auxiliary machines with either the condenser or with the atmosphere according to whether or not the main engine 1 and condenser 2 are in operation, and for a detailed 75 description of said valve 10 I refer to the said applications. In this instance the following description will suffice.

The regulating valve is provided with an inlet 15 connected to the exhausts 9 as seen 80 in Fig. 1, and with the outlets 11 and 12 aforesaid. The inlet 15 communicates with a valve chamber 16 having two ports 17 and 18, leading to the outlets 11 and 12 and controlled by valves 19 and 20. The valve 19 is fast on the valve stem 21 while the valve 20 is slidably mounted thereon. A shoulder 22 limits the upward movement of the valve 20 and serves also as a means to close the same. Below the valve 10 is mounted an 90 abutment 23 by means of bolts 24 which also supports a cylinder 25 in which moves a piston 26 fast to the valve stem 21. 27 is a spring secured to the abutment 23 and the piston 26. The cylinder 25 forms a pressure chamber below the piston, which chamber is connected to the condenser 2 by pipes 28, 29 and 70 having a valve 29, see Fig. 1. 95

When the main engine 1 and the condenser 2 are in operation, the pressure in the 100 pressure chamber within the cylinder 25 is reduced by way of pipes 28 and 70 and consequently piston 26 is moved down by atmospheric pressure, which overcomes the force of the spring 27 with the result that 105 the valve 17 is opened and the valve 18 is closed as shown in Fig. 2.

If now one or more of the auxiliary units are operated, the exhaust steam therefrom will pass through the exhaust pipe or pipes 110

9 to inlet 15 in valve 10, thence through the valve chamber 16 and out through the open port 17, outlet 11 and to the condenser 2.

If, however, unit 1-2 ceases to operate, the pressure in the cylinder 25 will rise until at a predetermined pressure (less than atmospheric) the spring 27 lifts the piston 26 and closes port 17 by the valve 19. If none of the auxiliary units are in operation, both 10 of the valves 19 and 20 will remain closed, but if one or more of the auxiliary machines are operated, the exhaust steam therefrom will lift the valve 20 up against the shoulder 22, which has been moved up by the 15 spring 27, thereby opening the port 18 through which the steam will pass to the atmosphere through outlet 12. When the main engine resumes operation, the pressure in cylinder 25 will again be reduced, the 20 piston moves down and closes valve 20 and opens valve 19 and the exhaust steam will again pass into the condenser 2.

In each of the exhaust pipes 9 there is connected a check valve 30. For some of 25 the auxiliary machines an ordinary check valve may suffice, but for the generator unit 4 or like unit in which it is desirable that the check valve operates against a constant pressure, I prefer to use a check valve of 30 the construction shown in Figs. 3, 4, and 5 which illustrate the preferred form of my improved present check valve.

As shown, the valve comprises a casing 31 having the inlet 32 and outlet 33 connected in the pipes 9 in the usual manner. 35 34 indicates the valve which controls the passage of the steam. Above the valve is provided a pressure chamber 35 connected by a pipe 36 to the pipes 28 and 70 and 40 hence to the condenser 2, see Fig. 1. The pressure chamber is closed with a diaphragm 37, carried by a stem 38 which is connected by the yoke 39 to the valve stem 40. Both 45 of the stems 38 and 40 are adjustably connected to the yoke 39 by nuts 41, 41 and 42, 42 as shown. It follows that the stems 38 and 40 operate as practically a single valve stem.

When the main engine 1 and condenser 50 2 are operated, the pressure in the check valve chamber 35 is reduced by way of pipes 36, 28 and 70 and the diaphragm 37 will be depressed under atmospheric pressure on the upper side thereof. Consequently the 55 yoke 39 will be pressed downward and the valve 34 will be closed under atmospheric pressure. If now one of the auxiliary units commences to work, the exhaust steam therefrom will pass through pipe 9 and valve 60 65 inlet 32 into the check valve, lift the valve 34 against atmospheric pressure and thence pass into the regulating valve 10 and through the latter into the condenser as above set forth. During this operation it is obvious that the exhaust steam operates

against atmospheric pressure only and not against the vacuum in the condenser which acts to draw the diaphragm down and the valve 34 up, and the force of which may therefore be disregarded and only the atmospheric pressure tending to seat the valve is a factor of resistance against the passage of the steam through the check valve 30.

If, however, the main engine and condenser are shut down, the exhaust steam 70 passes through the regulating valve 10 to the atmosphere as set forth above. Consequently the pressure in chamber 35 increases until there is atmospheric pressure below the diaphragm, whereby the atmospheric 80 pressure on top thereof is neutralized and the steam lifts the valve 34 against the atmospheric pressure through the regulating valve 10 and common exhaust 13. Or in other words, also when the main engine and 85 condenser are shut down, does the exhaust steam work against atmospheric pressure the same as when they are in operation. In the case of the generator unit it is quite necessary that the exhaust steam at all times 90 works against a constant pressure to prevent racing and overloading when the pressure varies. And it will be desirable or necessary also in the case of other auxiliary power units requiring similar conditions. Again, it 95 is obvious, that I do not intend to limit the use of my pressure check valves to marine steam plant installations, but intend using it wherever a constant pressure check valve is desirable or demanded. Without the check 100 valve 30 the auxiliary units 4 and 5 exhaust against either the low pressure in the condenser (when the latter is operated) or against a much higher pressure, namely atmospheric pressure (when the condenser is 105 not operated). That is to say, the auxiliary units exhaust against varying pressures dependent upon whether the condenser is operated or not. In case of the generator unit, the lowering of the back pressure (from atmospheric to condenser) will cause the generator to race and perhaps cause the insulation to burn or cause other damage unless the supply steam passing into the unit is cut down. The advantage of employing the 115 check valve 30 is first and foremost that a constant back pressure is obtained for the auxiliary units, and this in turn may lead to the elimination of the governor on the auxiliary units, and in the case of the generator unit will prevent melting of fusible parts and other damage.

There are obviously other factors than the mere differences in pressures to be considered. Thus the weight of the yoke 39, inaccuracies in construction, differences due to the different coefficients of elasticity of diaphragms of different materials and the like must also be considered. In addition to the means whereby the positions of the stems 125 130

38 and 40 may be adjusted with respect to the yoke to compensate for possible stiffness on the part of the diaphragm and regulating the position of the valve 34 and which 5 has been explained, I provide means to vary the effective surface of the diaphragm in order to regulate and adjust the pressures within the valve 30.

To this end I provide a plurality of members 45 adapted to slide radially in the annular portion 46 of the pressure chamber casing 47. Each slide 45, in this instance four, carries a pin 48 which moves in a groove 49 in the annular adjusting member 50 which is provided with an operating handle 51. When the said handle 51 is operated, the annular adjusting member or ring 50 is rotated and through the instrumentality of the grooves 49 and pins 48, the 20 four radial slides are caused to move radially inward or outward. 52 and 53 are packings and 54 is a top ring for keeping the member 50 in position. The ring 54 is provided with a scale 55 and the handle 51 25 carries a pointer 56. Two of the opposed slides 57 and 58 carry each a semi-circular flexible member 59 which is adapted to lie against the inner curved ends of the other two slides 45.

30 When it is desired to vary the effective surface of the diaphragm, the adjusting member 50 is rotated which causes the slides to move radially inward as set forth above and whereby the semi-circular flexible members 59 are moved toward each other or caused to close up, so that they and the slides form a smaller circle within which the diaphragm is either depressed or raised as is obvious. By this means the effective 35 surface of the diaphragm may be adjusted or varied as required to insure that the valve 34 is operated against a constant pressure.

In order to obtain quick action when the main engine and condenser cease to operate, 40 it is necessary that the pressures in the pressure chambers in the regulating valve and the check valve be simultaneously and quickly increased or decreased as the case may be. To this end I provide an air valve 45 60, see Fig. 6, connected to the pipes 28, 36 and 70, between the condenser and the said valves as seen in Fig. 1, and which pipes communicate with the said pressure chambers. The air valve comprises a casing having an 50 air inlet 61 and two air outlets 62 and 63. The inlet is controlled by a valve 64 and the outlet 63 is controlled by a valve 65, both of 55 said valves being fast on a valve stem 66. 67 is a spring tending to open valve 65. The 60 air outlet 62 communicates with the pressure chambers in the valves 30 and 10 through the pipes 28 and 36. The air outlet 63 leads to the condenser 2 by way of the pipe 70. The operation is as follows:—

65 During the operation of the main engine

and condenser, the valve 65 is open by atmospheric pressure because vacuum exists on the "condenser side" of the valve 64 and if the auxiliary unit is operating, the exhaust steam therefrom will pass through 70 check valve 30, against atmospheric pressure as explained, pipe 9 and the regulating valve 10 into the condenser. If now the main unit ceases to operate, the pressure will increase on the condenser side of valve 64 until 75 such pressure plus the force of spring 67 opens the valve 64, when air will be admitted through inlet 61 into the pressure chamber 35 in the check valve by way of pipes 28 and 36 so that the check valve will 80 continue to lift against atmospheric pressure only (in pipe 9) and not lift against any pressure on the diaphragm 37. At the same time that the valve 64 is opened, valve 65 is 85 closed and prevents further reduction of the vacuum in the condenser.

It will therefore be noted that not alone have I provided means for automatically passing the exhaust steam from the auxiliary units to the atmosphere or to the condenser according to whether the latter is 90 shut down or operating, but I have also provided means whereby the exhaust steam at all times operates against a constant pressure while the means 60 serves the purposes 95 indicated.

The combination of the regulating valve and the check valve will obviously increase the efficiency and safety of operation of the entire power plant by means which are simple 100 in construction and automatic in action.

I claim:—

1. The combination with a steam engine, a condenser therefor, a second steam engine, a passage leading from the exhaust of said 105 second steam engine to the said condenser, means in said passage for automatically connecting the exhaust of said second engine with the said condenser, when the latter and said first named steam engine are operating, 110 or connecting said exhaust with the atmosphere, when said first engine and condenser are not operating and a check valve in said passage for causing a constant back pressure against the admission of the exhaust steam 115 from the said second steam engine to either the said condenser or to the atmosphere.

2. A steam power plant installation comprising a steam engine, a condenser therefor, a plurality of other steam engines, means 120 for connecting the exhausts of the latter with the said condenser, when said first named steam engine and condenser are operating, or connecting the said exhausts with the atmosphere when said first engine and 125 condenser are not operating, and means for causing a constant back pressure against the admission of the exhaust steam from each of said other engines to either the said condenser or to the atmosphere. 130

- 4
3. A steam power plant installation comprising a steam engine, a condenser therefor, a plurality of other steam engines, means for connecting the exhausts of the latter with the said condenser, when said first named steam engine and condenser are operating, or connecting the said exhausts with the atmosphere when said first engine and condenser are not operating; and means for causing a constant back pressure equal to atmospheric pressure against the admission of the exhaust steam from each of said other engines to either the said condenser or to the atmosphere.
- 10 4. The combination with a steam engine, a condenser therefor, a second steam engine, of a passage leading from the exhaust of the latter to the said condenser, pressure regulated means in said passage for automatically connecting the said exhaust with the condenser, when the latter and said first named engine are operating, or connecting the said exhaust with the atmosphere when the condenser and said first engine are not operating, means in said passage for exerting a constant back pressure against the admission of the exhaust steam to either the said condenser or to the atmosphere and
- 15 20 25

means for admitting air to the said pressure regulated means when the pressure in the condenser rises to a predetermined point.

5. The combination with a steam engine, a condenser, a plurality of other steam engines, of mechanism for connecting the exhausts from the latter to either the atmosphere or the said condenser, and means in said mechanism for exerting a constant back pressure against the passage of the exhaust steam from each of the said other steam engines to either the said condenser or to the atmosphere.

6. The combination with a steam engine and a condenser, of a valve comprising a casting having an inlet connected to the exhaust of the said engine and an outlet connected to the said condenser, a valve controlling the communication between said inlet and outlet, a pressure chamber formed in said valve casting, a diaphragm for closing said pressure chamber, a passage leading from the latter to the said condenser, and a connection between said diaphragm and valve.

Signed at New York, in the county of New York and State of New York, this third day of March, A. D. 1917.

CLAUS LEVINSEN.
